DESIGN FOR A COMBINED TANK HOLDER AND PEDESTAL THEREFOR

Rallston M. Sherman, Glastonbury, and Malcolm
R. Knox, Hartford, Conn.

Application April 18, 1935, Serial No. 56,457

Term of patent 14 years

To all whom it may concern:

Be it known that we, Rallston M. Sherman and Malcolm R. Knox, citizens of the United States, residing, respectively, at Glastonbury and Hartford, county of Hartford, and State of Connecticut, have invented a new, original, and ornamental Design for a Combined Tank Holder and Pedestal Therefor, of which the following is a specification, reference being had to the accompanying drawing, forming a part thereof.

Figure 1 is an elevational view of the combined tank holder and pedestal therefor, illustrating

our design, the pedestal being shown in dotted lines.

Figure 2 is a top plan view thereof.

The dominant feature of the design resides in the tank holder, shown in full lines.

We claim:

The ornamental design for a combined tank holder and pedestal therefor, as shown and described.

RALLSTON M. SHERMAN.
MALCOLM R. KNOX.
